UNITED STATES PATENT OFFICE.

FREELAND W. OSTROM, OF BRIDGEPORT, CONNECTICUT, ASSIGNOR TO THE WHEELER & WILSON MANUFACTURING COMPANY, OF SAME PLACE.

SEWING-MACHINE FOR STITCHING AND CUTTING BUTTON-HOLES.

SPECIFICATION forming part of Letters Patent No. 463,295, dated November 17, 1891.

Application filed May 18, 1891. Serial No. 393,154. (No model.)

To all whom it may concern:

Be it known that I, FREELAND W. OSTROM, of Bridgeport, county of Fairfield, State of Connecticut, have invented an Improvement 5 in Sewing-Machines for Stitching and Cutting Button-Holes, of which the following description, in connection with the accompanying drawings, is a specification, like letters on the drawings representing like parts.

10 This invention is an improvement on that described in United States Patent No. 439,680, dated November 4, 1890.

The machine described in said patent has a blade carried by a cutter-bar parallel to the 15 needle-bar, and to avoid interfering with the needle-bar during the stitching operation the cutter-bar is provided with means whereby when the cutter is not to operate the bar is elevated and partially rotated to turn the 20 blade aside out of the path of movement of the needle-bar and needle; but when the blade is to cut a button-hole in the material, then the cutter-bar in its downward movement is partially rotated to thus place the cutting- 25 edge of the blade centrally with relation to the work-clamp and to the rows of stitching; as preferably the blade will descend after the stitches have been made to constitute the worked edges for the button-hole. The blade 30 with one operation cuts the button-hole for its entire length. In some instances, to avoid contact of the blade with the needle-bar, the latter has been grooved longitudinally at one side to receive the front end of the cutter.

35 Figure 1 in front elevation represents a sufficient portion of a button-hole sewing-machine with my improvements added to enable the same to be understood. Fig. 2 is a left-hand side view of the machine shown in Fig. 1.

40 The bed or cloth plate A of the machine, the overhanging arm A', the needle-bar B⁵, the needle-bar-actuating rock-shaft B², its arm B³, link B⁴, the work-clamp T, throat-plate t, cutter-bar-actuating rock-shaft B', and its arm b 45 are and may be all as in said Patent No. 439,680, so need not be further described more than to say that the cutter-bar-actuating rock-shaft may in practice be turned to actuate the cutter-bar and cut a button-hole 50 as and by means such as described in said

patent, or by any other usual equivalent means whereby the cutter by one stroke will cut a button-hole. Preferably the time at which the cutter shall act will be governed or controlled by some device moved by the work-clamp or feeding device as provided for in 55 said patent. To avoid oscillating the cutter-bar and its blade, as described in said patent, I have provided the overhanging arm or head of the machine with cutter-bar bearings which are inclined with relation to the vertical plane in which the needle-bar reciprocates, as thereby I am enabled to support the cutter in a diagonal position with relation to the needle-bar. 60

In the machine in which my invention is herein embodied I have shown the usual ears at the head of the overhanging arm as extended, as represented in Fig. 1 at the left, and through these ears I have made diagonal 65 holes for the reception of the bearings e e, in which moves the cutter-bar e', so that the said bar occupies a diagonal position with relation to the needle-bar, as shown. 70

The cutter-bar has clamped adjustably 75 upon it a block or collar c², provided with a stud e³, (represented by dotted lines in Figs. 1 and 2,) the inner end of which stud enters a guide slot or way e⁴, made in a lug e⁵, attached to or forming part of the overhanging arm, 80 the said guideway being substantially parallel to the longitudinal center of the cutter-bar. The stud e³ is embraced by the bifurcated end of the arm b of the cutter-bar-actuating rock-shaft, and when the said rock-shaft 85 is moved, as provided for in the said patent, to depress the said arm the cutter-bar will be thrown down and the blade, to be described, carried thereby will cut the button-hole. It will also be obvious that the cutter-bar is 90 raised as the arm b is lowered. By loosening the screw t in the block or collar c² the cutter-bar may be raised or lowered and turned more or less about its center, in order to bring the blade g' in just the proper alignment with relation to the slot in the button-hole clamp 95 and with relation to the material held in the clamp. The lower end of the cutter-bar, as shown, is provided with a web or flat part attached thereto by a suitable screw 2. This 100

web has in its face a groove, which, as represented, receives a fin 5, projecting from an upright part 3 of the blade-holder *g*, having cheek-pieces under the control of a screw 4, 5 by which to cause the cheeks to clamp the blade *g'*. The web *f* is slotted, so that the screw *f'* passes through it, as represented by dotted lines, so that the blade-holder may be adjusted laterally with relation to the longitudinal center of the work-clamp or so that the blade may be adjusted exactly central with relation to the throat of the work-clamp. The shape of the blade and the location of the cutter-bar are such that the bar, having 10 only a movement of reciprocation in a right line, may be thrown down or depressed just when the button-hole is to be cut and without any possibility of interfering with the movement of or contacting with the needle or 15 needle-bar.

I claim—

A work-clamp, a needle-bar and needle, a cutter-bar mounted in a diagonal or inclined position with relation to the needle-bar, a blade carried by the said cutter-bar, an adjustable collar applied to the said cutter-bar and having a stud, an actuating device to act upon said stud, and thereby reciprocate the cutter-bar, and a guideway for the said stud, the said guideway being parallel, or substantially so, to the longitudinal center of the cutter-bar, to operate substantially as described. 25

In testimony whereof I have signed my name to this specification in the presence of two subscribing witnesses.

FREELAND W. OSTROM.
